Monika L. Jaansson, Esq.

(57) **CLAIM**

The ornamental design for a cap designed to reseal a partially used tube of caulk for later reuse, as shown and described.

DESCRIPTION

FIG. 1 is a left side perspective view of a cap designed to reseal a partially used tube of caulk for later reuse;
FIG. 2 is a left side perspective view of the cap of FIG. 1;
FIG. 3 is a right side perspective view of the cap of FIG. 1;
FIG. 4 is a rear view of the cap of FIG. 1;
FIG. 5 is a front view of the cap of FIG. 1;
FIG. 6 is a top view of the cap of FIG. 1;
FIG. 7 is a bottom view of the cap of FIG. 1; and,
FIG. 8 is a perspective view of the cap of FIG. 1 positioned on a partially used tube of caulk for later reuse.
The portions of the tube of caulk shown in broken lines depict environmental subject matter only and form no part of the claimed design. The broken line portion of the cap in FIG. 7 forms no part of the claimed design.

1 Claim, 8 Drawing Sheets
